UNITED STATES PATENT OFFICE.

HENRY C. SWAN, OF OSHKOSH, WISCONSIN.

FIFTH-WHEEL FOR VEHICLES.

SPECIFICATION forming part of Letters Patent No. 623,342, dated April 18, 1899.

Application filed October 31, 1898. Serial No. 695,012. (No model.)

To all whom it may concern:

Be it known that I, HENRY C. SWAN, a citizen of the United States of America, residing at Oshkosh, Winnebago county, State of Wisconsin, have invented certain new and useful Improvements in Gear-Irons for Vehicles, of which the following is a specification in such full, clear, and exact terms as to enable any person skilled in the art to which it appertains to make, construct, and use the same.

The annexed drawings and the following description set forth in detail one mechanical form embodying the invention, such detail construction being but one of various mechanical forms in which the principle of the invention may be used.

In said annexed drawings, Figure I represents a top plan view of my device; Fig. II, a bottom plan view; Fig. III, a bottom plan 20 of the upper disk; Fig. IV, a top plan of the lower disk; Fig. V, a cross-section on the lines 5 5, Fig. I; Fig. VI, a cross-section on the lines 6 6, Fig. I; Fig. VII, a sectional view of the perch secured in the perch-socket; Fig. VIII, a sectional detail view showing 25 the perch-socket before the perch has been clamped therein.

In my improved gear-iron the lower disk 1 is circular in outline and is secured to the 30 front axle 2 by any suitable means, such as standards 3, provided with flanges 4 and clips 5. A projection 6 is formed centrally of said disk and integral therewith. Segments 7, raised above the surface of the disk, are provided across the axis of the disk parallel to the axle of the vehicle. Said segments extend only a suitable distance on either side of the axis, providing recesses 8 between their adjacent ends and are adapted to register 35 with each other. The faces of the segments are suitably finished to form smooth bearing-surfaces. A circular upper disk 9 is provided with an annular flange 10 of sufficient diameter to fit snugly over the periphery of the lower disk. Centrally of said upper disk a recess 11 is formed, corresponding in outline to the projection 6. Bearing-segments 12 are provided on the upper disk, corresponding with the segments on the lower disk and 45 adapted to register therewith. Perch-sockets 13 are formed integral with the upper disk, whereby the upper disk may be secured to

the perches 14 of a vehicle. Said perch-sockets are provided with depending flanges 15, that extend below the center of the perch and 55 are adapted to be closed in and around the perch after the same is seated. If a square perch is used, the flanges engage the sides of the perch, both square and round perches being well known and in common use. 60

A spring-chair 16 may be secured to the upper disk by any suitable means, such as rivets or bolts 17, passing through perforations in the base of the spring-chair and in the upper disk. If this manner of fastening 65 is used, the rivets or bolts are constructed so as to hermetically seal the openings provided in the disk.

A clevis 18 passes under the axle at right angles thereto and is provided at its ends 70 with screw-threaded portions 19. Said screw-threaded portions are secured in lugs 20, integral with the upper disk at the front and rear thereof, by means of the nuts 21, arranged in pairs above and below the lugs. A spring- 75 bar 22, provided with eyes 23, passes under the lower disk and is secured upon the clevis between the lower pair of nuts and the bottoms of the lugs. A short projection 24 is preferably formed on the bottom of the lower 80 disk, that has a bearing on the bar. That portion of the clevis beneath the axle is provided with a projection 25, engaging a corresponding recess 26, provided in the under side of the axle. Said projection forms a pivot 85 upon which the axle turns and also holds the clevis in its proper position.

In practice the segments of the upper disk rest upon the segments of the lower disk and slide thereon. The segments provide the 90 only horizontal bearing between the disks and receive the entire weight of the vehicle. By raising the segments above the respective surfaces of the disks no bearing is provided either at the center or at the front and rear of the 95 disks. When a flat bearing-surface or an annular bearing-ring is provided, the sides of the bearing wear more rapidly than the center or the front and rear portions on account of the unequal loading of the vehicle. The 100 inequalities of the bearing-surface thus formed causes rocking of the vehicle and also interferes with the proper working of the gear.

The central projection formed on the lower

disk bears no part of the load and is provided merely for the purpose of centering the disks upon each other. The annular flange also assists in centering the disks, and the central 5 projection may be dispensed with entirely if the flange is constructed sufficiently strong to withstand the strain.

By forming the perch-sockets integral with the annular flange and the upper disk and 10 providing the sockets with flanges that can be closed in and around the perch I dispense with a lower perch-strap and at the same time obtain a rigid and secure attachment between the perch and the disk.

15 The disks are secured from upward displacement by means of the bar and clevis. In ordinary use it is unnecessary to use both the clevis and bar; but for greater security I prefer to use both. If it is desired to dispense 20 with the clevis, the yoke is severed at the screw-threaded portion, or the clevis may be removed entirely and the bar secured by any well-known means, such as a bolt or nut. The spring-bar is secured under the depend- 25 ing projection of the lower disk at considerable tension. This causes sufficient friction between the bearing-segments to prevent unnecessary movement of the disks upon each other and also prevents rattling of the gear.

30 The edge of the lower disk adjacent to the bottom of the lugs provides a bearing for the spring-bar, that enables it to hold the disks securely against displacement. Only in case of accident or of an unusually violent strain 35 is the clevis necessary to reinforce the bar. The nuts that secure the clevis or bar in the lugs afford means for suitable adjustment of the disks. Frequent adjustment is unnecessary, as the tension of the spring-bar is suffi- 40 cient to prevent lost motion that would otherwise result from wear of the bearing-segments. By this construction I also dispense with the king-bolt, and as no opening is provided through either disk the gear-iron is 45 formed practically dirt-proof. Foreign substances can gain access to the bearing-sur- 50 faces only by passing up between the depend- ing flange and the periphery of the lower disk. If by chance any foreign substance enters 55 this opening, it is carried downward by its own weight and by the action of the adjacent sur- faces upon each other. When a king-bolt is used, it is necessary to provide an opening through the centers of the disks. This open- 60 ing must be slightly larger than the diameter of the king-bolt in order that the lower disk may revolve. The size of the opening increases gradually as a result of wear, and dirt

and other foreign substances are permitted to enter the bearing freely, thereby impairing 60 the efficiency and interfering with the proper working of the gear.

What I claim is—

1. In a gear-iron for vehicles, two imperforate disks having segmental bearing-surfaces 65 at their sides and recesses at their front and rear between said surfaces, and means for centrally guiding said disks, and means for holding same together, substantially as described.

2. In a gear-iron for vehicles, the combination with two disks having circular-outlined bearing-faces, of a tension-spring secured to the upper disk and engaging under the lower disk and coming in central contact therewith, 75 substantially as described.

3. In a gear-iron for vehicles, the combination with two disks having circular-outlined bearing-faces, of a clevis secured to the upper disk and passing under the axle, and a spring- 80 bar secured upon said clevis and passing under the lower disk, substantially as described.

4. In a gear-iron for vehicles, the combination with a lower disk, and an upper disk provided with an annular flange and an integral 85 perch-socket, said disks having segmental bearing-surfaces for rotating upon each other, of a clevis secured in lugs integral with the upper disk and passing under the lower disk, and means upon said clevis for adjusting said 90 disks, substantially as described.

5. In a gear-iron for vehicles, the combination with an upper disk, of a perch-socket integral with said disk and provided with depend- 95 ing flanges adapted to be closed in and around the perch, substantially as described.

6. In a gear-iron for vehicles, the combination with a lower disk secured to the axle, and an upper disk secured to the frame by integral perch-sockets and provided with an 100 annular flange embracing the periphery of the lower disk, said disks having segmental bearing-surfaces that correspond with and rotate upon each other, of a clevis secured to the upper disk and having a pivotal bearing under the axle, and a bar secured to said clevis 105 passing under the lower disk and providing a bearing for said disk, substantially as described.

In testimony whereof I sign this application, 110 in the presence of two witnesses, this 25th day of October, 1898.

HENRY C. SWAN.
